UNITED STATES PATENT OFFICE.

HARALD F. GADE, OF PHILADELPHIA, PENNSYLVANIA, ASSIGNOR TO STANDARD PRESSED STEEL CO., OF PHILADELPHIA, PENNSYLVANIA, A CORPORATION OF PENNSYLVANIA.

SHAFT-HANGER.

1,283,406.

Specification of Letters Patent. Patented Oct. 29, 1918.

Original application filed June 15, 1910, Serial No. 567,081. Divided and this application filed December 18, 1915. Serial No. 67,622.

To all whom it may concern:

Be it known that I, HARALD F. GADE, a subject of the King of Norway, (having declared my intention of becoming a citizen 5 of the United States,) and a resident of Philadelphia, Pennsylvania, have invented certain Improvements in Shaft-Hangers, (being a division of my application for patent for improvements in shaft-hangers filed 10 June 15, 1910, Serial No. 567,081,) of which the following is a specification.

My invention relates to shaft supporting structures, and it consists of a novel and improved form of shaft hanger in which the 15 supporting legs and feet and the portion receiving the journal-box are formed of pieces of suitably rolled commercial metal sections.

The improved structures forming the subject of my invention are preferably made of 20 single pieces of commercial metal sections which are bent or otherwise formed into the desired shape or contour of a shaft hanger whereby I am enabled to provide a simple and efficient hanger structure at low cost. 25 While I prefer to effect the bending or shaping of the shaft hanger at a single operation, it will be understood, of course, that in some instances the bending or shaping of the metal to form the desired hanger may require more than one operation. 30

Combined spacing and bracing members are provided to connect the legs and support one of the positioning members for a journal-box.

These and other features of my invention will be more fully pointed out hereinafter, reference being had to the accompanying drawings, in which:

Figure 1, is a front elevation of a shaft 40 hanger made of a section or strip of flat metal, the legs of which are reinforced or strengthened by a pressed-up rib intermediate the edges of the strip;

Fig. 2, is a side elevation of the same; 45 Fig. 3, is a sectional view of a flat strip from which the form of hanger shown in Figs. 1 and 2 is made;

Fig. 4, is a sectional view on the line IV—IV, Fig. 1;

50 Fig. 5, is a front elevation of a hanger made from a rolled metal shape, T-form in cross section;

Fig. 5^a, is a plan view of the same, partly in section;

Fig. 6, is a side elevation of the hanger 55 shown in Fig. 5;

Fig. 7, is a front elevation of a hanger made from a rolled metal shape, I-form in cross section;

Fig. 8, is a side elevation of the same; 60

Fig. 9 is a cross sectional view on the line IX—IX, Fig. 7;

Fig. 10, is a side elevation of a shaft hanger made from a commercial channel bar, which may be additionally strengthened 65 at the journal supporting portion by pressing a hollow rib in the web of the same;

Fig. 11, is a side elevation of the same;

Fig. 12, is a front elevation of another 70 form of hanger made from a commercial channel section, having a special form of cross brace between the legs of the hanger;

Fig. 13, is a side elevation of the same;

Fig. 14, is a plan view of a channel section, with the central portion of its web removed preparatory to forming a hanger of 75 the type shown in Figs. 12 and 13;

Fig. 15, is a view similar to Fig. 14, showing the web of the channel member pushed together to close the space from which the 80 metal has been removed;

Fig. 16, is a sectional view on the line XVI—XVI, Fig. 12;

Fig. 17, is a view of a modified form of hanger resembling the structure shown in 85 Fig. 1, and

Fig. 18, is a sectional view on the line XVIII—XVIII, Fig. 17.

My improved hanger or hanger frame consisting of rolled metal shapes, which may 90 be standard commercial sections bent or otherwise shaped into the desired form, constitutes a shaft or journal supporting portion 1, legs 2, and feet 3, and the elements noted, in the forms of structure shown in 95 the accompanying drawings, are preferably comprised in a single piece.

As shown in the several views, the side portions of the lower part of the hanger or frame are substantially parallel with each 100 other up to the point α , and at such point a combined bracing and connecting member 4 is preferably provided, shown by full lines in certain of the views, and by dotted lines

in other views. This bracing member may be made of sheet metal suitably pressed into shape; having flanges 5 whereby it may be riveted to the legs of the hanger as shown at 6, and with an upper wall 5^a providing with the side walls a socket portion for the reception of a lock-nut 7 employed in connection with an upper adjusting screw 8, whereby said lock-nut may be held against turning.

In the form of hanger shown in Figs. 1 and 2, I employ a flat metal section such as illustrated at 10, in Fig. 3, and to strengthen or stiffen the legs of the hanger when made of such metal shape, I provide them with a hollow rib 11, more clearly illustrated in Fig. 4. In this form of hanger, the cross brace is made of sheet metal riveted to the hanger legs, and serves as a support for the upper vertically disposed adjusting screw 8, and the nuts employed therewith. A lower vertically disposed adjusting screw 8^a may be threaded through the bottom loop 1^a of the hanger, or secured in any other suitable manner. This portion of the hanger may be provided with a struck-up boss 12 forming a seat for a lock-nut 7^a, or a separate filler piece may be employed. A journal-box for receiving and supporting a shaft is shown at 13.

In Figs. 5 and 6, another form of hanger is shown made of metal T-shape in cross section; the central web or rib 14 of the section being disposed outwardly as indicated. In this structure, the journal-box 13 may be carried by a cradle 15 supported by the lower portion of the hanger, while the brace 4 connecting the legs carries an adjusting screw 8, with the usual lock-nuts.

Other forms of metal sections may be employed in the production of hangers made in accordance with my invention, and in Figs. 7, 8 and 9, I have shown a structure made of metal I-shape in cross section; Fig. 9 being a sectional view on the line IX-IX, Fig. 7. At the foot portion of the structure, the flanges on one side of the central web are removed, as indicated at 16, to form the feet, as clearly illustrated in Figs. 7 and 8.

In Figs. 10 and 11, I have shown a hanger frame made of a channel member substantially U-shape in cross section; the central web of which may be further strengthened by providing the same with a rib 18, which may extend from a point near the feet to the lower connecting curved part of the journal-box-supporting-portion of the same.

In Figs. 12 and 13, I have shown, respectively, a front elevation and a side view of a hanger made of a channel section of metal, which is preferably reduced in width at the lower curved journal-box-supporting-portion. This may be accomplished by remov-

ing a portion of the metal from the web of the same, as illustrated at 20 in Fig. 14; the outer portions of the channel section being then pressed together as shown in Fig. 15. The side legs of this structure may be held together by a brace 4^a disposed substantially at the center of the legs. The character of this brace is clearly shown in Fig. 16. It comprises a pair of flanged members 21, recessed at the center to form a space 22, receiving the upper adjusting screw 8. In assembling this connecting member with the hanger, solid plates 23 are preferably interposed between the flanges of the hanger legs and the flanges of the members 21 forming the brace, and these several parts are preferably secured by rivets 24.

In Figs. 17 and 18, I have shown a shaft hanger or hanger frame, somewhat like those shown in Figs. 1 and 5, made of metal T-shape in cross section; parts of the central web or rib 14^a having been removed adjacent the feet and the journal-box-supporting-portion. In this form of my improved structure the outer face of said ribs preferably extends in a substantially single plane from the lower portion of the hanger to the feet.

In all instances I prefer to provide a bracing piece connecting the legs intermediate the same, and in some instances I may connect the upper ends of the legs adjacent the feet by a suitable bracing member which may be substantially like that disclosed in my pending application before referred to and of which this application is a division.

It will be noted further that the position of the journal-box may be adjusted by the vertically disposed screws 8 and 8^a, and that I prefer to omit adjusting screws at the sides of the journal-box.

While I have referred to the use of sheet metal bracing and spacing members between the legs of the hanger, it will be understood that other forms of metal braces may be employed without departing from my invention.

I claim:

1. As a new article of manufacture, a shaft hanger comprising a continuous section of commercial structural metal bent to form a pair of legs and a journal-box-supporting portion continuous with said legs; said legs being reinforced longitudinally by a rib formation externally disposed and being flared outwardly, and the upper ends of the outwardly flared legs being shaped to terminate in substantially horizontal feet outwardly disposed, a cross brace connected to the legs between the walls of the same, and journal-box positioning means carried by said cross brace.

2. As a new article of manufacture, a shaft hanger comprising a continuous section of commercial structural metal bent to form a

pair of legs and a journal-box-supporting portion continuous with said legs; each of said legs being reinforced by a pressed-up rib formation externally disposed and being flared outwardly, and the upper ends of the legs being shaped to terminate in substan-

tially horizontal feet outwardly disposed, a cross brace disposed between the legs and having flanges whereby it may be secured to said legs, and a journal-box positioning screw carried by said cross brace.

HARALD F. GADE.
